HAND MIRROR

Irene I. Levis, 51 Arundel Place, Clayton, Mo.

Filed July 13, 1960, Ser. No. 61,352

Term of patent 3½ years

(Cl. D86—10)

The essential features of my design reside in the hair, eyes, and nose appliqued upon a facial background mounted on the back and the edges of the mirror as shown.

I claim:

The ornamental design for a hand mirror, substantially as shown and described.
